METAL-AND-WOOD SHOVEL HANDLE

William W. Wood, 3d, Piqua, Ohio, assignor to The
Wood Shovel & Tool Company, Piqua, Ohio, a
corporation of Ohio

Application September 14, 1932, Serial No. 633,107

3 Claims. (Cl. 294—57)

This invention relates to metal-and-wood shovel handles having a contour resembling the "Split-D" handle.

Formerly all-wood shovel handles were in general use, but as lumber of kinds suitable for shovel handles became more and more scarce, and correspondingly costly, a demand grew up for handles that required less material.

This growth has been gradual. There was a time when practically all shovel handles were of the so-called "Wood-D" type. As the need for economy in lumber became apparent a wooden handle known as the "Split-D" was developed, which handle required less than one-third as much lumber as the old "Wood-D" handle. The "Wood-D" has a grip portion or head about $4\frac{1}{2}$ inches wide formed upon a round stave or stem, the whole being made of a single piece of wood. The "Split-D" can be made from a piece of wood no wider or thicker than is necessary to make the stem of a "Wood-D". But both types require pieces of wood of substantially the same length.

The requirement for still further economy of wood having arisen, metal heads were developed to take the place of the "Wood-D" heads, thereby reducing the length of the piece of wood necessary to make the stave. These metal heads were usually made to imitate the contour of the old "Wood-D" handles, more or less. The metal part of my handle resembles the "Split-D" in contour.

One object of my invention is to still further reduce the length of the piece of wood necessary in making a shovel handle. Another object is to produce a metal handle of such length that it can be attached to the stave of a shovel whose head has become damaged, or even broken off at or near where it joined the stave. In this way many shovels that are otherwise in good condition can be restored. Still another object is to produce a light, strong metal handle of practical form and graceful proportions.

I shall now proceed to describe my invention with the aid of the accompanying drawing, in which,

Fig. 1 is an elevational, sectional view of my improved handle, including a short section of the wooden stave;

Figs. 2, 3 and 4 are transverse sectional views of the handle, taken, respectively, on the lines indicated on Fig. 1;

Fig. 5 is a side view of one-half of the metal part of the handle, looking toward the inside of the part;

Fig. 6 is a transverse sectional view of one arm of the handle, on line 6—6 of Fig. 5, and

Fig. 7 is a side elevation of the complete handle, with a small portion broken away to expose a modification of the structure.

While the so-called "Split-D" handle is well known in the shovel trade, it may be well to explain here, briefly, how such a handle is made. At its head end a round stave is sawed down the middle a distance of nine inches, more or less, producing two prongs semi-circular in cross-section, and a rivet is put through the stave at the point where the saw cut ends. The prongs are bent outward at their lower ends and then their upper ends are bent inward, a wooden grip being secured between their extremities. Thus the prongs become the arms of a bifurcated handle. The two bends, in opposite directions, give to the arms a slightly S-shape. In Fig. 1 of the accompanying drawing the arms 10—10 are given a contour resembling that of the arms of a "Split-D", and Fig. 6 has the contour of the arms in cross section.

Referring now to the several figures in the drawing, the handle is seen to comprise two arms, 10—10, and a stave-socket 11, in which a wooden stave 12 is secured with rivets 13—13. A wooden grip 14 is confined between the upper ends of the arms 10—10, the arms being provided with hemi-spherical sockets 15 to receive the hemi-spherical ends 16 of the grip. The sockets 15 are bound to the grip with a tight metal band 18, which ties in grooves 17 in the sockets 15, and in grooves, not shown, formed in the sides of the grip. This arrangement for securing the grip to the arms is fully illustrated and described in Patent No. 1,843,120, granted Feb. 2, 1932, on the application of C. L. Butts.

The metal part of my handle is formed from two sheet metal blanks, each bent to form one-half of the handle. Each comprises a portion or zone that constitutes one-half of the stave-socket 11, joined to which, longitudinally, is one arm 10 of the handle. The blank is bent longitudinally to a semi-circular form, and by two sharp longitudinal bends the excess metal at each side of the blank is bent inward, as at 25—25, Fig. 6, causing the portions 26—26 of the blank to abut at 27. Thus the metal not needed to form the semi-circular wall of the arm becomes the flat inner wall of the arm, and the contour of the arm becomes D-shape in cross-section. The portions 26 of the blank, in the zone that becomes the stave-socket 11, are cut away, leaving edges 28—28 (Fig. 5), which edges are in the

same plane as the flats 26. Therefore, when the edges 28 of the two half-handles abut to form a whole stale-socket the flats of the two halves are brought into contiguity for a short distance, as in Fig. 1, forming a key 29 that extends down into the socket. It is to be understood, of course, that in bending the blanks into tubular form, they are not only given the D-shape cross-section, but they are also given the S-shape necessary to give the resulting handle the contour of the "Split-D" handle. At their upper ends the parts 26-26 are cut to an arcuate shape, as at 30-30, so they will fit up to the grip 14, as in Fig. 1. Preferably, the edges 28 of the halves 10 of the stale-socket are welded together. But the edges may be united by other means, for example, as in the handle shown in the Shirray patent, No. 601,987, where the edges of the stale-socket are united with the well known Tinner's lock 15 seams. Just how the edges of the halves of the socket are united is a matter of design. In fact, it is not essential that the edges be attached. This will be referred to presently.

A kerf is cut across the end of the stale 12, 25 which the key 29 enters as the stale is forced into the socket 11. One of the rivets 13 passes through the key. This rivet serves as an abutment for the handle, enabling the shovel to sustain great longitudinal pressure on the handle 30 in either direction. The key supports the center of the rivet and enables the handle not only to sustain heavy longitudinal pressure, but even severe shocks, as when the handle is used as a tamping bar. Furthermore, the key supplements the rivets 13 as a means for keeping the handle from turning on the socket, hence its name, "key".

The kerf in the stale serves as a means for holding the arms 10 together at the point where 40 they join the stale-socket. It is this which makes it feasible to dispense with welding or other means for fastening the edges of the halves of the socket together, relying upon the rivets 13 to hold the parts of the socket in position.

45 The modification shown in Fig. 7 consists in omitting the rivet that passes through the key 29. With this arrangement it is not necessary to cut the kerf in the end of the stale very deep. One object of this modification is that the stale 50 may be a little shorter than where the rivet passes through the key 29. This would result in a slight reduction in the cost of the stakes. Another object is to reduce the cost of a shovel by omitting one rivet. The principal advantage obtained, however, is in replacing handles on damaged shovels. If the stale of the shovel is broken off in such a way that to use two rivets, as in Fig. 1, will make the handle a little too short, the trouble may, in many cases, be overcome 55 by using only one rivet, as in Fig. 7.

It is not to be understood that my invention

is limited to the specific embodiment shown, as various modifications are possible without departing from the spirit of my invention, or exceeding the scope of the appended claims.

Having shown and described what I now regard as the preferred embodiment of my invention, I claim:

1. A metal-and-wood shovel handle, comprising two sheet metal blanks, each bent to form one-half of a hollow bifurcated handle, each half comprising a zone that constitutes one-half of a stale-socket, said zone joining longitudinally a tubular arm of D-shape cross-section, the flat of the D and the edges of said half-socket being in the same plane, thereby causing the flats of the two arms to be contiguous when the edges of the half-sockets abut to form a complete stale-socket, the contiguous flats combining to form a key that extends down into the socket, and a wooden stale, the upper end of which is confined in said socket, a kerf cut across the extreme end of the stale, embracing said key.

2. A metal-and-wood shovel handle, comprising two sheet metal blanks, each bent to form one-half of a hollow bifurcated handle, each half comprising a zone that constitutes one-half of a stale-socket, said zone joining longitudinally a tubular arm of D-shape cross-section, the flat of the D and the edges of said half-socket being in the same plane, thereby causing the flats of the two arms to be contiguous when the edges of the half-sockets abut to form a complete stale-socket, the contiguous flats combining to form a key that extends down into the socket, a wooden stale, the upper end of which is confined in said socket, a kerf cut across the extreme end of the stale, embracing said key, and a rivet which passes through the two halves of the socket, through the stale and through said key.

3. A metal-and-wood shovel handle resembling in contour a wooden handle of the "Split-D" type, comprising two sheet metal blanks, each bent to form one-half of a handle having the contour of a "Split-D" handle, each half comprising a zone that constitutes one-half of a stale-socket, said zone joining a tubular arm of D-shape cross-section, the edges of the blank abutting in the flat wall of the D, said flat of the D and the edges of said half-socket being in the same plane, thereby causing the flats of the lower portions of the two arms to be contiguous when the edges of the half-sockets abut to form a complete socket, the contiguous flats combining to form a key that extends down into the socket, and a wooden stale having a kerf cut across its extreme end inserted in the socket, the kerf embracing said key, the portion of the stale in the region of the key and socket, being free from inimical strains tending to disintegrate the wood.

WILLIAM W. WOOD, 3RD.
